UNITED STATES PATENT OFFICE.

HARRY F. JOSEPH, OF DAVENPORT, IOWA, ASSIGNOR, BY MESNE ASSIGNMENTS, TO
B. L. SCHMIDT COMPANY, A CORPORATION OF SOUTH DAKOTA.

INTERNAL-GRINDING MACHINE.

1,396,123.

Specification of Letters Patent.

Patented Nov. 8, 1921.

Application filed August 7, 1920. Serial No. 401,988.

To all whom it may concern:

Be it known that I, HARRY F. JOSEPH, a citizen of the United States, residing at Davenport, in the county of Scott and State 5 of Iowa, have invented certain new and useful Improvements in Internal-Grinding Machines, of which the following is a specification, reference being had to the accompanying drawings.

10 This invention relates to grinding machines, and particularly to machines for grinding the inner or outer faces of automobile cylinders, pistons, pins, valves, and in fact, all parts commonly found on automobiles, though it is obvious the invention is not limited to the use for which it is particularly designed, as it might be used for grinding cylinders or other parts for other mechanisms.

15 The general object of the invention is to provide a mechanism of this character including a grinding wheel which is rotatable and at the same time may be moved in a circle around the central longitudinal axis 20 of revolution or may be rotated without moving bodily around the central axis.

A further object in this connection is to provide means whereby the feed of the grinding wheel may be controlled, this 30 mechanism being such that the grinding wheel may be fed in either direction while the machine is running.

A further object is to provide means whereby the rapid adjustment of the grinding wheel may be made by hand when the main bearing supporting the grinding wheel and its parts is idle.

A further object is to provide means whereby water may be supplied to the grinding wheel and whereby this water may be thrown by the centrifugal action of the wheel outward to the face of the work being acted upon.

A further object is to provide means whereby the water used which is thrown outward against the work shall keep the grinding wheel spindle cool at all times.

Another object is to provide means which prevents the oil from the bearings of the 50 grinding wheel spindle from getting upon the grinding wheel and prevents dust from the grinding wheel getting into the bearings.

A further object is to provide a guard for use in external grinding to throw the water 55 upon the revolving work.

A further object is to provide very simple and effective means whereby the grinding wheel may be adjusted while the spindle is rotating and while the spindle and grinding wheel are moving in a circular path, and 60 whereby the grinding wheel and spindle may be fed in one direction or the other as desired.

And a further object is to provide means whereby the engagement of the driving worm 65 with the worm gear may be adjusted to take up wear.

Other objects will appear in the course of the following description.

My invention is illustrated in the accompanying drawings, wherein:—

Figure 1 is a side elevation of an internal grinding machine constructed in accordance with my invention;

Fig. 2 is a rear end elevation of the machine;

Fig. 3 is a fragmentary vertical sectional view through the housing 10 and a portion of the base B taken on the line 3—3 of Fig. 4;

Fig. 4 is a detail rear elevation of the housing and bearings for the spindle;

Fig. 5 is a fragmentary vertical sectional view through the rear end of the spindle and the bearings therefor showing the water 85 ducts in section;

Fig. 6 is a fragmentary longitudinal sectional view through the forward end of the spindle and the grinding wheel mounted thereon;

Fig. 7 is a section on the line 7—7 of Fig. 6;

Fig. 8 is a section on the line 8—8 of Fig. 3 but showing the spindle in its lowermost position;

Fig. 9 is a sectional view on the line 9—9 of Fig. 8;

Fig. 10 is a top plan view of the construction shown in Fig. 8;

Fig. 11 is a sectional view on the line 100 11—11 of Fig. 10;

Fig. 11^a is a fragmentary elevation looking from the rear of the feeding mechanism illustrated in Fig. 8;

Fig. 12 is a detail elevation partly in 105 section of the joint between the spindle members 24 and 37;

Fig. 13 is a section on the line 13—13 of Fig. 12;

Fig. 14 is an elevation of the guard 102 110

in applied position, the spindle housing being broken away;

Fig. 15 is a detail side elevation of the guard with its shank.

Referring to the drawings, and particularly to Fig. 1, it will be seen that my mechanism as a whole includes the base A, a supporting column B wherein the spindle and spindle operating mechanism is supported, as will be later described, and a work support C which is mounted for longitudinal movement upon the power driven table D and consists of a plurality of relatively adjustable sections whereby the work may be shifted longitudinally of the table, transversely of the table, or rotated relative to the longitudinal axis of the table, and whereby the work may be held at any desired elevation. This mechanism, which I have designated generally A, B, C and D forms no part of my invention, my present invention residing in the means whereby the spindle carrying the grinding head is rotated and given a bodily movement around a central axis, and whereby water is supplied to the grinding wheel.

Referring to Fig. 3, it will be seen that the column B has rotatively mounted therein an approximately cylindrical carrier 10 which is provided intermediate its ends with the gear 11. This cylindrical carrier is provided at its ends with the inwardly directed, annular flanges 12 and 13 forming bearings for a spindle housing 14. This member 10 may be rotated by any suitable mechanism, but I have illustrated for this purpose a shaft 15 carrying a pinion or gear wheel engaging the gear wheel 11 and driven by a belt or sprocket chain 16, in turn operating over a belt wheel or sprocket wheel 17 carried upon the shaft 18 driven by a sprocket chain 19 from a sprocket wheel 20 on a motor shaft 21, the motor being designated 22. I do not wish to be limited, however, to the particular means for driving the member 10. This member is entirely inclosed within the housing formed by the column B and the cap B' thereof.

Disposed within the cylindrical carrier 10, as previously stated, is the spindle housing 14, which is annular in cross section, and this spindle housing 14, as indicated clearly in Fig. 4, is eccentrically disposed with relation to the carrier 10 so that as this carrier 10 rotates in the direction of the arrow in Fig. 4, the spindle housing will be carried bodily around the axis a, and it will be seen from Fig. 3 that this spindle housing 14 has a passage 23 which is eccentric to the periphery of the spindle housing. Extending through this passage 23 is a spindle, designated generally 24, and which, as illustrated, is composed of the two sections. This spindle is considerably longer than the spindle housing and projects beyond the spindle

housing both at its forward and rear ends. Extending from the body 14 of the spindle housing is the front spindle housing 25 within which the forward portion of the spindle 24 is disposed and in which it is rotatably mounted. The forward end of the spindle 24 is mounted in exteriorly conical bearings 26, (see Fig. 6) while that portion of the spindle coincident with the rear end of the forward spindle housing 25 is mounted in 75 bearings 27 which are likewise conical.

The forward end of the housing 25 is screw-threaded, and engaged therewith is a collar 28 having an annular flange 29 extending over the end of the bearing 26 and 80 by rotating this collar it is obvious that the wear on the bearing may be taken up. The spindle is reduced at this point, as at 30, and surrounding the reduced portion of this spindle and bearing against the forward 85 flange 29 of collar 28 and extending over the forward portion of this collar 28 is a dust cap 31 which rotates with the spindle 24. Surrounding the body of the dust cap 31 is the grinding wheel 32 which may be 90 an emery grinding wheel or carborundum grinding wheel, or a grinding wheel of any suitable character, the face of this grinding wheel being cut out at its center, as at 33. The extremity of the spindle 24 is screw- 95 threaded, and engaging this screw-threaded portion is a nut 34 having radially extending, relatively shallow passages 35, (see Fig. 7) and riveted to this nut is a plate 36. The spindle has a longitudinally extending bore 100 37 by which water is supplied to the grinding wheel, and this bore flares toward its forward end and discharges water into the radial ducts 38 and by these radial ducts 105 the water is discharged against wheel 32 and carried outward by centrifugal action against the work.

The rear end of the spindle 24 projects beyond the cylindrical housing 14. This housing 14 is cut out at its rear end to receive certain ball bearings, as will be later stated, and mounted upon the spindle 24 are the two connected driving pulleys 38 and 39 which are keyed or otherwise connected to the spindle 24 to rotate therewith. The ball 115 bearing for the support of the rear end of the spindle may be of any suitable construction, and as illustrated in Fig. 5 comprises an inner member 40, the outer annular member 41, and the intermediate anti-friction element, such as anti-friction balls. This ball bearing is held in place by means of a jam nut 42 exteriorly threaded to engage the interior threads on the recess formed in the rear end of the housing 14, as most clearly 120 illustrated in Fig. 5. The rear end of the housing 14 is exteriorly screw-threaded for engagement by the nuts 43, whereby the housing is held in proper relation to the rotatable carrier 10, which has an annular 125 130

plate 10^a attached to it by screws and against which the nuts 43 bear, the forward end of the housing section 14 having a flange 44 which bears against the split ring 43^a. The nuts 43 pull the spindle housing 14 against the split ring 43^a on the forward end of the spindle housing and push the rear split ring 43^b against end flange plate 10^a. This insures perfect bearing at all times. Thus, 5 the housing section 14 is supported for relatively rotary movement within the rotatable carrier 10 and the spindle is supported for rotation around its own axis within the housings 14 and 25. Preferably this 10 spindle is formed in two sections, as shown in Fig. 12, one of the sections being screw-threaded, as at 45, the other section having a head 46 of the same diameter as the screw-threaded section, this head being formed 15 with a central, conical boss 47 seating within the end of the other section, and these two parts being held from relative rotation by pins 48. The two sections are held together by a flexible coupling member 49 having 20 a flange to engage over the head 46 and being interiorly screw-threaded to engage over the screw-threads 45. This coupling member is held in place by a jam nut 50.

It will be noted from Fig. 12 that the 30 exterior face of the boss 47 is slightly curved or struck on a radius and that the rear face of the shoulder 46 also has a curve corresponding to the radius of the curvature on the outer face of the boss 47 to thereby allow 35 for flexibility in the coupling at this point, the pins 48 being relatively loose in the sockets formed in the part 24 to permit this.

At its rear end, the spindle carries means 40 whereby it may be connected to a water supply pipe and to a pipe for carrying off excess water, and to this end, as illustrated in Fig. 5, the bore 37 at the rear end of the spindle is flared, as at 51, and this rear end of the spindle is exteriorly screw-threaded. Surrounding 45 the rear end of the spindle is a hollow head 52 which is interiorly screw-threaded at its rear end, and disposed within this screw-threaded portion of the head is a housing nut 53 which is annular and carries 50 a conical nozzle 54. This conical or tapered end is disposed within the flared rear end 51 of the bore 37, this nozzle being provided with a shoulder disposed between the nut 53 and the rear end of the spindle. Surrounding 55 and rotating with the spindle 24 are the internal bearing members 55 and 56 separated by an internal spacing collar 57. Balls or other anti-friction elements 58 surround the bearing members 55 and 56 and 60 roll against the outer bearing members 59 and 60 which fit within the head 52. The central, outer spacing collar 61 separates the outer bearing members 59 and 60. The bearing members 55 and 56 with the collar 65 57 are forced against the conical projecting end 39^a of the pulley 39 by means of a nut 62 engaging the screw-threaded rear end of the spindle 24. The rear extremity of the nozzle 54 projects out beyond the nut 52 and is exteriorly screw-threaded for engagement 70 with the interior screw-threads of an elbow 63 which is connected by a flexible pipe 64 to a source of water. The water is preferably forced through this pipe by a rotary pump (not shown). The housing nut 53, as 75 will be seen from Fig. 5, is formed with a port 65 at one point in its circumference, and this port alines with a passage 66 leading from the head or housing 52, and forms the means whereby the overflow from the 80 housing or head may be carried off, this outlet branch 65 connecting to a flexible pipe 67. It will, of course, be obvious from the above description that the spindle can rotate freely within the housing 14 and within the 85 head or housing 52 and with reference to the nozzle 54, and that water may be continuously supplied to the port of the spindle and that overflow will be carried off from the branch 66. The overflow passes out through 90 the space between the extremity of the nozzle 54 and the flared end 51 of spindle 24. Should there be no overflow space water would be forced into the ball bearings. This overflow also allows drainage when 95 supply of water is cut off.

In order to provide means whereby the grinding wheel may be adjusted toward or from the axis *a* around which the grinding wheel rotates to thereby finely adjust the 100 depth of cut, I provide means whereby the housing section 14 and the housing section 25 with it may be axially rotated. To this end, I mount upon the forward end of the carrier 10 an approximately annular plate 105 68 (see Figs. 3 and 8) having an eccentrically disposed, circular opening 69 which fits over the flange 44 of member 14 and which is provided with a marginal flange 70 fitting over an annular rabbet or recess 110 formed in the forward end of the carrier 10. This plate 68 carries at one point on its periphery a bearing bracket 71 supporting a shaft 72 which, at its rear end, carries a ratchet wheel 73, having radially projecting 115 teeth. The opposite end of this shaft 72 carries a worm 74. This worm meshes with a worm wheel 75 loosely mounted on a shaft 76 carried in bearings 77 on the plate 68. One face of the worm wheel 75 carries upon 120 it the clutch teeth 78, and coacting with these clutch teeth is a clutch member 79 mounted upon the shaft 76. A coiled compression spring 80 bears against one of the bearing lugs 77 and against a collar 81 carried by the shaft 76 so that normally the clutch member 79 is urged into engagement with the clutch teeth 78 and thus the worm wheel 75 is clutched to the shaft 76. This shaft between the bearing members 77 car- 125 130

ries a worm 82, and at one extremity carries a knurled hand wheel or knob 83. The plate 68 is mounted upon the carrier 10, and surrounding the extremity of the spindle housing 14 is a worm gear wheel 84. This worm gear wheel 84 has its central opening concentric to the axis of the worm gear. This worm gear wheel is attached to the housing members 14 by screws 85. Worm 82 is keyed to shaft 76 by key 82^a.

Coacting with the ratchet wheel 73, as will be later described, and mounted upon the housing section B' and, therefore, held stationary relative to the rotation of plate 15 68 and bracket 71 is an upwardly projecting bracket 86 having two passages for the two longitudinally shiftable pins 87 and 88 (see Figs. 10 and 11). The walls of the pin passages in the bracket 86 are slotted, as at 89, 20 and ears 90 project from the pins 87 and 88 and extend into said slots. The rear ends of the pins 87 and 88 are headed, as at 91, and springs 92 urge these pins rearward, that is retract the pins. Mounted upon 25 these pins are the triangular cams 108 and 109. The cam 108 has its angular face, that is the hypotenuse of the triangle, facing downwardly and toward the left in Fig. 8. The other cam 109 has its inclined face or 30 hypotenuse facing upwardly, this triangular face extending downward and toward the left in Fig. 8. Either of these cams is adapted to be manually projected into active position by pressing on the appropriate 35 knob 91, but is normally retracted by the spring 92 and held thereby out of active position.

Mounted upon the shaft 72 rearward of the ratchet wheel 73 is a pawl carrying lever 40 110. This lever is rotatable with relation to the shaft 72 and is held in place by the screw 111. The ratchet wheel 73 is, of course, fast on shaft 72. This lever projects laterally from its axis in one direction to form 45 the relatively long arm of the lever, and the outer end of this arm is provided with a rearwardly projecting pin 112 carrying a roller 113, as shown best in Fig. 11^a, which roller is adapted, as the plate 68 is rotated, 50 to engage with whichever cam 108 or 109 is projected. This lever 110 carries upon it the substantially triangular pawl 114, which is triangular in form to provide the oppositely projecting teeth 115 and 116 engageable with the ratchet wheel 73. The apex of the triangular pawl is engaged by a spring 55 pressed pin 117 urged toward the pawl by a spring 118, as shown in Fig. 10. The extremity of this pin 117 is rounded and bears 60 against the rounded apex of the pawl and yieldingly holds the pawl in one or the other of its active positions. The opposite extremity of the lever 110 is formed with a reentrantly angled face 119, and disposed on 65 a bracket or lug 120 projecting from the

bearing member 71 is a spring projected pin 121 projected toward the angular face 119 of the lever by means of a spring 122. Extending from the bracket 71 and specifically from the bearing portion of this bracket is 70 a lug or extension 123 having a forwardly projecting lug 124 constituting a stop. The base of this bracket 71 is also formed with a forwardly projecting lug 125 constituting a stop. The pawl 114 is adapted to engage 75 with one or the other of these stops. Thus, for instance, referring to Fig. 11^a, when the pawl carrying lever 110 moves downward beyond a certain point, the tooth 116 of the pawl 114 will strike the stop 125 and this 80 will shift the pawl 114 so as to bring its tooth 116 in engagement with the teeth of the ratchet wheel 73 and bring the tooth 115 out of engagement with the teeth of the ratchet wheel 73. On the other hand, if the 85 tooth 116 is engaged with the ratchet wheel 73, then upon an upward movement of the roller carrying end of the lever 114 beyond a certain point, the tooth 115 will strike the stop 124 and the position of the pawl will be 90 reversed. It will be seen that when the operator presses upon one or the other of the pins 87 or 88, the corresponding cam 108 or 109 will be projected into the line of rotation 95 of roller 113, this roller being carried around with the plate 68 and with the main bearing. The roller strikes and glides upon the corresponding cam, and when it is struck the inclined end face of this cam will force the roller downward in one direction, and the 100 pawl 114 will carry the ratchet wheel around in one direction, thus giving a partial revolution to the ratchet wheel 73 and giving a partial rotation to the worm 74. This being engaged with worm gear 75, revolves the 105 worm gear, which in turn revolves the worm 82 and the worm gear wheel 84, thus making an adjustment of the emery wheel cut by moving the worm gear wheel 84 which is attached eccentrically to the rear spindle housing, said housing supporting the front spindle housing 25. After the roller 113 has traveled over the cam, as for instance the cam 108, and has moved off this cam, the 110 lever 110 is brought back to its neutral position by spring plunger 121. When a reverse adjustment of the feed is required, the operator forces out cam 109, for instance, and the roller 113 will move over the upper face 115 of this cam, thus shifting the lever in the opposite direction and thus feeding the ratchet wheel in the opposite direction and feeding the spindle oppositely. The pin which has been shifted to the proper position to operate the cam 108 will, of course, need to be 120 shifted to a reverse position in order to operate the cam 109, and when the operator carries the cam 109 into position to engage the roller, the tooth 115 of pawl 114 will 125 strike the stop 124, thus throwing the pawl 130

into opposite center of the spring plunger 117 and causing the tooth 116 to engage the ratchet teeth. If the pawl strikes the cam 108, a reverse action takes place and the depression of the lever will cause the pawl to strike the stop 125 and the pawl will again be reversed. Thus the pawl is kept in one position or the other until the opposite cam is projected. Of course, as soon as pressure 10 is released from the press buttons 91, either cam will be retracted away from the line of rotation of the roller 113.

For rapid adjustment of the wheel, the operator presses upon the knob or wheel 83, which disengages the clutch member 79, thereby releasing all the automatic feed mechanism, and then by rotating the wheel or knob 83, a direct and rapid adjustment may be secured in the manner above indicated through the action of the worm 82 on the worm wheel 84. Upon the release of the knob or wheel 83, the clutch member 79 is automatically reengaged with the worm gear wheel 75.

It is desirable to provide means whereby the engagement between the worm gear 84 and the worm 82 may be adjusted to take up wear. To this end, the front plate 68 is attached to the carrier or main bearing 10 by means of cap screws 93 passing through slots 94 in the plate 68. Attached to the plate 68 by means of a screw 95 is an eyebolt or adjusting screw 96, through the eye of which the screw 95 passes, the shank 35 being threaded. This screw-threaded shank 96 passes through a stud 97 which is screwed in the end of the carrier or main bearing 10. The screw 96, of course, passes loosely through the perforation in the stud 97 and 40 on each side of this stud are disposed the knurled nuts 98 and 99. By releasing the cap screws 93, the front plate 68 can be drawn around circumferentially by turning the knurled nut 99, which action draws the 45 worm 82 into deeper mesh with the worm gear 84. After the desired adjustment has been made, the parts are locked in their adjusted position by the lock nut 98 and the cap screws 93.

It will be noted that the pivotal axis of the bearing plate 68 is equi-distant from the axis of rotation of the housing 10 and the axis of rotation of the spindle 24, thus permitting the axis of the spindle 24 to be 50 located in coincidence with the axis of the housing.

It will be seen from Figs. 1 and 2 that the flexible pipes 64 and 67 extend downward through slot 100 which is formed in a yoke 101 which is rotatably mounted in and projects from the housing wall formed by the supporting column B. This yoke 101 is a freely oscillatable yoke and thus takes care of the independent eccentric action of 55 the head or elbow 52 and permits the free

movement of the pipes 64 and 67 rendered necessary by this eccentric action of the various parts.

The work carriage C may be of any suitable design or character and is provided with means whereby it may be longitudinally shifted toward or from the grinding wheel and the work raised or lowered, or the work turned into any desired angle with the axis of the grinding wheel. Of course, 70 it will be understood that other work supporting means may be used in connection with the movable feed table D, and for various kinds of work, as for instance, rods, pins, cylinders, pistons, etc., and that where 80 rods or pins are to be ground, the rod or pin or other work will be rotated and carrier 10 will be idle while spindle 24 will rotate around the axis a, and that the same is true of grinding the exterior of a cylinder or piston, but that when interior work is to be ground, the grinding wheel is disposed within the hollow article and revolves around the central axis a. Where external grinding is being done, a guard, such as 90 shown in Fig. 14, will be used. This guard 102 is approximately semi-circular in form and embraces the grinding wheel and is provided with a shank portion 103 having clamps whereby it may be engaged with the 95 spindle housing. This guard is preferably in two halves hinged together and is clamped upon the main spindle housing 25 in any desired position. Water will strike the guard and be thrown off upon the revolving 100 work. The pump which supplies water to the spindle is controlled by a knob 104 which, when shifted inward, throws the pump out of gear when the water supply is not desired, and which, when pulled outward, throws the pump into gear. A lever 106 (see Fig. 1) is used for shifting the clutch (not shown) which allows for throwing idle the main bearing 10, that is for causing power to be transmitted to this main 110 bearing 10 or carrier. The throwing of this main bearing 10 idle does not, of course, stop the revolution of the spindle carrying emery wheel. The lever 107 is used for changing the speeds of the movable base D. The 115 clutch mechanism controlled by the lever 106 and the means for securing variable speeds of the table D have not been illustrated, as it is not believed necessary, as these parts are more or less old and well 120 known.

I have not shown in detail the means for operating the work support to thereby feed the work, nor have I shown any means for controlling the speed of the various shafts or 125 the rotating speed of the spindle, or the speed of revolution of the spindle and its grinding wheel around the central axis a, as these may be of any desired and obvious construction.

The general operation of this mechanism will be obvious from what has gone before. The article to be ground or operated on is supported on the movable work support and 5 adjusted to the proper position, and the carrier or main bearing 10 is then rotated through the gear 11 and at the same time the spindle is rotated through the pulleys 38 or 39. When grinding internally, the spindle will be rotated, rotating with it the 10 grinding wheel and at the same time the grinding wheel and spindle will move bodily around the axis α . By the means heretofore described, the spindle and grinding wheel 15 may be shifted radially outward or inward, as desired, either automatically by forcing in one or the other of the pins 87 or 88, or by disconnecting the clutch 79 the feed may be rapidly controlled by means of the wheel 20 83. The feeding means which I have devised provides for an extremely fine adjustment of the feed capable of feeding the cut in fractions of thousandths of an inch while the machine is running. The particular 25 construction of the grinding wheel and the means for supplying water thereto provides for the water being sprayed outward by centrifugal force against the face of the work where the wheel is in direct contact 30 with the work, thereby producing a maximum feed at the point of engagement between the wheel and the work. At the same time, this water passing through the grinding wheel spindle acts to keep the spindle 35 cool. Obviously other liquids than water might be used if desired.

While I have illustrated a construction which has been found thoroughly effective for the purpose intended, yet it will be obvious 40 that many modifications might be made in the details of construction and arrangement of parts without departing from the spirit of the invention.

I claim:—

- 45 1. In a mechanism of the character described, a tubular spindle, a grinding wheel mounted thereon and having a recess in one end face, a nut engaging the spindle and bearing against the grinding wheel and disposed in said recessed end face, the outer 50 face of said nut having radially extending grooves, and a baffle plate attached to said nut and extending over said recesses therein.
- 55 2. In a mechanism of the character described, a tubular spindle reduced at one end having an exterior screw-threaded extremity, the bore of the spindle flaring toward its extremity, a grinding wheel surrounding the reduced extremity of the 60 spindle and having a recess in its outer end face, and a nut engaging the screw-threaded extremity of the spindle and disposed within said recess, said nut having radial discharge ducts communicating with 65 the bore of the spindle, and a baffle plate

attached to the face of said nut and forming the outer wall of the said ducts.

3. In a mechanism of the character described, a tubular, rotatable spindle, a hollow head into which the end of the spindle extends, bearings mounted in said hollow head supporting the spindle, a nozzle carried in the hollow head and projecting loosely into the bore of the spindle, and a supply pipe connected to the nozzle. 75

4. In a mechanism of the character described, a tubular, rotatable spindle, a hollow head into which the end of the spindle extends, bearings mounted in said hollow head supporting the spindle, a nozzle carried in the hollow head and projecting loosely into the bore of the spindle, a supply pipe connected to the nozzle, and a discharge pipe connected to the head, the head having ducts communicating with the interior of the spindle to carry off the excess liquid. 80

5. In a mechanism of the character described, a tubular rotatable spindle, bearings supporting the spindle, a fixed hollow head into which the rear end of the spindle projects and open at its opposite ends, anti-friction bearing elements disposed within the hollow head and supporting the rear end of the spindle, a plug detachably closing the rear end of the head, a nozzle carried by said plug and discharging into the bore of the spindle, and a tubular water connection operatively engaged with the nozzle. 90

6. In a mechanism of the character described, a tubular rotatable spindle, bearings in which the spindle is supported, a fixed hollow head through which the rear end of the spindle projects and open at its opposite ends, anti-friction elements disposed within the hollow head and supporting the rear end of the spindle, a plug having screw-threaded engagement with the rear end of the head and having a central aperture, a nozzle having its body rotatably mounted in said aperture, said nozzle discharging into the bore of the spindle, and a tubular member detachably engaging the rear extremity of the nozzle and connected to a source of liquid supply. 100

7. In a mechanism of the character described, a tubular rotatable spindle, bearings supporting the spindle, a hollow head into which the rear end of the spindle projects, said head having an outlet, the bore 110 of the spindle at the extremity disposed within the head being outwardly flared, a member closing the rear end of the head, a nozzle rotatably mounted in said member and having a tapering forward end extending in to the flared extremity of the spindle, a water supply member operatively engaging the extremity of the nozzle, and means for holding the extremity of the spindle in spaced relation to the extremity of the nozzle. 120

125

zle whereby to leave an outlet space between the confronting faces of the spindle and nozzle, the head being formed with a discharge duct leading therefrom and into 5 which said space opens.

8. In a mechanism of the character described, a tubular rotatable spindle, bearings in which the spindle is mounted, a hollow head into which the rear extremity of 10 the spindle projects and having an inturned flange at its forward end, an outer ball race disposed against said flange within the head, an inner ball race mounted on the spindle, anti-friction elements disposed between the races, inner and outer spacing 15 sleeves abutted against the races, an inner and outer race disposed against the rear ends of the spacing sleeves, anti-friction members disposed between said races, a nut 20 engaging the rear extremity of the spindle and bearing against the inner rearmost race, a plug having screw-threaded engagement with the rear end of the head and having a central aperture, the plug being hollowed 25 out to form a circumferentially extending chamber surrounding said nut and having a discharge duct leading from said chamber, a nozzle rotatably mounted in the opening 30 of the plug and confronting the rear end of the spindle and discharging thereinto, the nozzle and rear end of the spindle being

spaced from each other to permit the discharge of water through said space into said chamber and duct, and a hollow water supply member engaged with the rear end 35 of said spindle.

9. A mechanism of the character described including a tubular spindle, a grinding wheel mounted thereon for rotation therewith, means for moving the spindle 40 bodily through a circular path eccentric to the axis of the spindle, means at the rear end of the spindle for forcing water into and through the tubular spindle, and means at the rear end of the spindle for carrying 45 off excess water.

10. A mechanism of the character described including a tubular spindle, a grinding wheel mounted thereon for rotation therewith, means for moving the spindle 50 bodily through a circular path eccentric to the axis of the spindle, means at the rear end of the spindle for forcing water into and through the tubular spindle, and means at the rear end of the spindle for carrying 55 off excess water, said means including flexible pipes and a swivelly mounted yoke through which the pipes pass.

In testimony whereof I hereunto affix my signature.

H. F. JOSEPH.
